United States Patent Office

Des. 201,512
Patented June 29, 1965

201,512

PLATE OR SIMILAR ARTICLE

Shigeru Masuda, 2185 Central Road, Apt. C,
Fort Lee, N.J.

Filed Jan. 8, 1965, Ser. No. 83,352

Term of patent 7 years

(Cl. D44—15)

The figure is a plan view of a plate or similar article showing my new design.

The plate is of conventional configuration when viewed from the side and bottom thereof.

I claim:

The ornamental design for a plate or similar article, substantially as shown and described.
